SPARK PLUG CLEANING MACHINE

Delmar E. Huffman, Oakland, Calif., assignor of twenty-five per cent to Jack C. Stone, Castro Valley, Calif.

Application January 26, 1954, Serial No. 406,150

7 Claims. (Cl. 134—142)

This invention relates generally to spark plug cleaning machines, and pertains more particularly to a machine of this type wherein a series of cleaning operations are performed in sequential relation to a plurality of spark plugs operatively associated with the machine.

A primary object of this invention is to provide an improved form of spark plug cleaning machine incorporating a rotatable turntable having a series of circumferentially spaced spindles thereon, each provided with a driving wheel and each being adapted to receive a spark plug, drive means being associated with some of the driving wheels and means being provided for selectively holding the turntable against rotation whereby the engaged driving wheels will rotate their respective spindles when the turntable is held against rotation and wherein the driving means will effect rotation of the turntable when the same is not held against rotation.

Another object of this invention is to provide a spark plug cleaning machine in conformity with the foregoing object wherein the turntable is mounted on a standard which includes a housing assembly provided with nozzle assemblies therein, the housing providing reservoirs for the reception of cleaning liquid and the nozzles being connected to a source of air under pressure connected through Venturi means to the cleaning liquid in the troughs for directing the cleaning liquid onto associated spark plugs.

Another object of this invention is to provide a spark plug cleaning machine in conformity with the foregoing objects wherein the housing is effectively sealed against leakage and splashing and wherein the entire assembly presents a compact and convenient unit readily adapted for the purpose intended.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is an elevational view of the machine;

Figure 2 is a vertical section taken substantially along the plane of section line 2—2 in Figure 1;

Figure 3 is a vertical section through the machine looking toward the front;

Figure 4 is an enlarged horizontal section taken substantially along the plane of section line 4—4 in Figure 3;

Figure 5 is an enlarged sectional view taken substantially along the plane of section line 5—5 in Figure 3;

Figure 6 is a view similar to Figure 5 but showing the other of the nozzle assemblies;

Figure 7 is a plan view of a peripheral portion of the turntable assembly;

Figure 8 is a plan view of a portion of the periphery of the turntable; and

Figure 9 is a perspective view of one of the latching members.

Referring now more particularly to Figures 2 and 3, the

2

machine is seen to consist essentially of a standard or housing indicated generally by the reference character 10 and which includes a front wall 12, a rear wall 14, a top wall 16 and a bottom wall 18. The housing also includes 5 the side walls 20 and an intermediate partition wall 22 parallel to the side walls and extending between the front and rear walls. Also extending between the front and rear walls is a bearing tube 24 into which a pair of spaced bearing members 26 and 28 are received for journaling 10 the axle member 30 in the manner shown. The axle member projects through the front wall 12 and has secured thereto the turntable member 32 such that the turntable may rotate with respect to the housing.

As seen most clearly in Figures 1, 2 and 5, the turntable 32 is provided with a series of circumferentially spaced bearings preferably in the form of bushings 34 for rotatably receiving the plurality of spindle members 36, each spindle projecting on opposite sides of the turntable and being provided on the outer side thereof with 20 a driving wheel or sprocket 38 in the manner shown. The opposite ends of the spindles are enlarged, as at 40, and are provided with longitudinal recesses for the reception of the spark plug assemblies indicated generally by the reference character 42. The engagement between the 25 spark plugs and the spindles may be effected in any desired manner, but is herein shown as a threaded engagement.

Since the inner or enlarged ends of the spindles project through the front wall 12, to permit rotation of the turntable 32, the front wall is provided with an annular slot 44 in registry with the various spindles. For effectively sealing this annular slot, the spindles carry an annular sealing plate member 46 whose opposite edges are arcuately deformed, as at 48, for engaging with circular bead members 50 secured to the front wall. These beads are 35 preferably formed of rubber or similar material to effectively seal with the opposite edges of the sealing plate 46.

To effect rotation of the turntable 32, the front wall 12 is provided with a base member 52 upon which a suitable motor assembly 54 is mounted and which includes a drive shaft 56 having a drive sprocket 58 thereon engaging with 40 an endless flexible drive element 60 which is trained about the several idler members 62 journaled on the front wall 12. The various idler wheels or sprockets 62 are so positioned on the front wall that the endless drive element 60 simultaneously engages several of the driving wheel assemblies 38 previously described. It will be manifest that as 45 the motor assembly 54 turns the drive sprocket 58, the endless drive element 60, shown in this case to be a chain, will effect rotation of the individual spindles and will also effect over-all rotation of the turntable assembly 32.

As seen most clearly in Figures 7—9, portions of the periphery of the turntable 32 are provided with serrations 64 for cooperation with the latching members 66 whose arcuate inner surfaces are serrated, as at 68, for engagement with the serrations on the periphery of the turntable. These latching members comprise opposite leg portions 70 and 72 each provided with an elongated opening 74, a transverse radial groove 76 being provided at the junction of the legs. Fastening elements 78 extend through 55 the elongated openings 74 into engagement with the periphery of the turntable 32, and it will be manifest that due to the elongation of the openings 74, the positioning of the latching assemblies 76 circumferentially of the turntable may be adjusted, the purpose of this adjustment 60 being presently apparent.

As previously stated, the partition wall 22 extends intermediate the side walls 20 such as to divide the interior of the housing into two separate compartments. In each of the compartments, the bottom wall 18 is depressed to form the troughs 80 and 82 for the reception 65 of the cleaning liquid 84. The front wall 12 is provided

with a U-shaped bracket member 86 within each of the compartments, the bracket being disposed in straddling relation to the sealing plate 46 and consequently, the various spark plugs 42 carried by the turntable. As seen most clearly in Figures 5 and 6, the brackets are for the purpose of supporting the various nozzle members 88, 90 and 92, the latter two nozzles being fan-shaped as shown and provided with the series of spaced discharge openings, the nozzles 92 being positioned to spray cleaning fluid on the upper ends of the spark plugs 42 while the other fan-shaped nozzle 90 is adapted to clean the threaded base ends thereof. The central nozzles 88 are provided with single discharge openings and are disposed slightly at an angle to the longitudinal axis of the spark plugs and are adapted to direct the cleaning fluid on the electrodes thereof. Thus, substantially the entire spark plug assembly is cleaned by the various nozzle assemblies 88-92. All of the various nozzle assemblies 88, 90 and 92 are directly connected together through suitable lines and are further connected to a line 94 extending from a suitable source of compressed air. Pick-up lines 96 are connected to the throat of a Venturi means in the inlet line 94 with the lower ends of the pick-up lines 96 being disposed within the liquid in the various troughs 80 and 82, such that as air under pressure is introduced through the lines 94, the cleaning fluid will be picked up and distributed to the various nozzles 88, 90 and 92 for discharge onto the spark plug assemblies.

To properly position the turntable 32 such that the spark plugs will be properly positioned for cleaning operation by the nozzle assemblies, the series of latching members 66 are provided. In setting up the machine, the various latching members 66 are so positioned on the periphery of the turntable 32 that their individual positions will correspond to the proper location of the various spark plug assemblies carried thereby. The purpose of these latching members 66 is to hold the turntable 32 in position against rotation for sequentially disposing the spark plugs for operation by the spray nozzle assemblies. In this respect, reference is had now more particularly to Figures 1 and 2 wherein it will be seen that the upper portion of the front wall 12 is provided with an electromagnetic assembly 98 having a movable core element or plunger 100 whose lower end is adapted to be engaged within the various notches 76 of the latching members 66. In this respect, it will be noted that the plunger 100 is urged normally by the spring 102 into the latching position. The latching engagement of the plunger 100 with the various latching members 66 is under control of the operator of the machine by virtue of the provision of the switch assembly 104 which, when depressed, will effect energization of the electromagnetic assembly 98 and retraction of the plunger 100 so that the turntable 32 will be permitted to rotate, release of the switch 104 permitting engagement of the plunger 100 with the next latching member 66 on the periphery of the turntable so that the turntable will then be held in the next position for the progressive and sequential cleaning operation of the various spark plug assemblies.

It will be noted that the turntable 32 extends upwardly or above the top wall 16 so that some of the spark plugs or spindles carried by the turntable are always exposed. The top wall is notched, as at 106, in registry with the annular slot 44 in the front wall 12 to permit passage of the spark plugs 42 therethrough. To effectively seal these notches 106, a pair of sealing strips 108 are secured to the opposite side edges of the notch with their inner beveled ends overlapping in the manner shown. In this respect, it will be noted that the partition wall 22 is also provided with a notch and associated sealing strips for passage of the spark plug therethrough.

As the machine is operated, the operator will remove the spark plugs which have had their cleaning operations completed, and will place new spark plugs to be cleaned in the machine. Although the direction of rotation as

shown in the drawings is intended to be counter-clockwise as viewed in Figure 3, it will be manifest that the direction of rotation is a matter of choice. It is also to be understood that the cleaning fluid 84 may be heated to more effectively clean the spark plugs and also to permit more rapid drying thereof, it also being within the province of this invention to provide suitable compressed air nozzles for blowing the cleaning fluid from the spark plugs after the wet cleaning operation. It is also within the province of this invention to provide a timing device for the manual switch 104 such that the cleaning operation will be effected in an entirely automatic manner.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly, all suitable modifications and equivalents may be resorted to, falling within the scope of the appended claims.

What is claimed as new is as follows:

1. A spark plug cleaning machine comprising a standard, a turntable rotatably mounted on said standard, a series of circumferentially spaced bearings on said turntable, a spindle journaled in each of said bearings, each spindle having a recess at one end for receiving a spark plug, drive means mounted on said standard and in engagement with some of said spindles to simultaneously effect a rotation producing force on both the spindles and the turntable, and means for selectively braking said turntable whereby the turntable may be held in fixed position while those spindles engaged by the drive means are rotated.
2. A spark plug cleaning machine comprising a standard, a turntable rotatably mounted on said standard, a series of circumferentially spaced spindles journaled in said standard, each spindle having a driving wheel secured at one end and being provided with a recess at its other end for receiving a spark plug, drive means including an endless flexible member operatively engaged with some of the driving wheels on said turntable, means for selectively holding said turntable in fixed position, said standard including a housing, a plurality of nozzles within said housing for sequentially directing fluid under pressure on spark plugs carried by said turntable.
3. In a spark plug cleaning machine, a housing having a front wall, a turntable journaled in said housing and disposed in spaced parallel relation to said front wall, a series of circumferentially spaced spindles on said turntable, each provided with a spark plug receiving recess, said front wall having an annular slot in registry with said recesses, and an annular seal plate secured to said spindles with its inner and outer edges overlapping said front wall on opposite sides of the annular slot.
4. The combination of claim 3 wherein said housing also includes a top wall, said top wall having spaced notches extending rearwardly from the annular slot in said front wall, and sealing strips extending inwardly from opposite sides of the notches, said sealing strips having their adjacent edges disposed in overlapping relation.
5. A spark plug cleaning machine comprising a standard, a turntable rotatably mounted on said standard, a series of circumferentially spaced spindles journaled in said standard, each spindle having a driving wheel secured at one end and being provided with a recess at its other end for receiving a spark plug, drive means including an endless flexible member operatively engaged with some of the driving wheels on said turntable, means for selectively holding said turntable in fixed position, the last named means including a retractable plunger on said standard and a series of circumferentially spaced latching members carried by said turntables sequentially engageable by said plunger.
6. A spark plug cleaning machine comprising a stand-

ard, a turntable rotatably mounted on said standard, a series of circumferentially spaced spindles journaled in said standard, each spindle having a driving wheel secured at one end and being provided with a recess at its other end for receiving a spark plug, drive means including an endless flexible member operatively engaged with some of the driving wheels on said turntable, means for selectively holding said turntable in fixed position, the last named means including a retractable plunger on said standard and a series of circumferentially spaced latching members carried by said turntables sequentially engageable by said plunger, said turntable being peripherally serrated and said latching members having teeth engaging the periphery of the turntable.

7. A spark plug cleaning machine comprising a standard, a turntable rotatably mounted on said standard, a plurality of circumferentially spaced spindles journaled in said turntable and projecting on opposite sides thereof, means for securing a spark to each spindle on one side of said turntable, a roller secured to each spindle on 15

5

the opposite side of said table, a drive wheel mounted on said standard, a plurality of idler wheels mounted on said standard, an endless flexible element trained about said drive and idler wheels and having the outer side of one flight thereof engaged with some of the spindle rollers, whereby movement of the flexible member will impart a rotation producing force to both the turntable and those spindle rollers engaged by the flexible element, means for selectively braking the turntable such as to prevent rotation of the turntable while those spindles having their rollers engaged by the flexible element will be rotated.
